UNITED STATES PATENT OFFICE.

THOMAS C. COOPER, OF CHICAGO, ILLINOIS.

LOCK.

Application filed July 18, 1918. Serial No. 245,447.

To all whom it may concern:

Be it known that I, THOMAS C. COOPER, a citizen of the United States, residing at Chicago, in the county of Cook and State of Illinois, have invented certain new and useful Improvements in Locks, of which the following is a specification.

This invention relates to improvements in locks and more particularly to locks of the type primarily adapted for use in connection with automobiles for the purpose of preventing any unauthorized removal of the spare tires carried thereby.

One object of the invention is to provide a lock of this character which shall be of rugged design, simple in construction and operation and economical to manufacture; one which may be readily and quickly applied and removed, and one wherein all of the operating parts are completely housed in such wise as to render the same inaccessible, all rivets and other fastening means being dispensed with.

Another object is to provide a lock of the type described which shall be designed to cooperate with the tire or its support to which said lock is applied in such manner that said tire or support will provide a barrier against any unauthorized tampering with the locking mechanism and in such manner as to effectively prevent any unauthorized removal of said lock.

Other objects and advantages will be apparent from the following description taken in connection with the accompanying drawings wherein two forms of the invention are illustrated.

Fig. 1 is a side elevation of the lock showing the same as applied to a plurality of tires.

Fig. 2 is a vertical longitudinal sectional view taken through the lock.

Fig. 3 is a rear plan view of the locking member with the cover removed.

Fig. 4 is a section taken on line 4-4 of Fig. 2.

Fig. 5 is a view illustrating the lock as applied to a single tire and its support, and

Fig. 6 is a side elevation illustrating a slightly modified form of lock.

Referring more in detail to the drawings, the lock is shown as comprising a staple or U-shaped member 10, preferably constructed of hardened steel. The shanks or legs of the staple 10 are preferably serrated or provided with a plurality of teeth as shown at

11, said shanks being designed to project through a plurality of apertured wings or lugs 12 disposed on opposite sides of the lock proper which is designated as a whole as 13. 60 The lock proper comprises preferably a malleable casting 14 which is designed to provide a housing for the entire locking mechanism and with this in view said casting is provided with a suitable chamber 15 65 adapted to receive said mechanism, the outer edges 16 of the side walls of said chamber being preferably curved inwardly substantially as illustrated in Figs. 1 and 2 of the drawings for the purposes to be hereinafter 70 pointed out. The end walls 17 of the casting are preferably provided with suitable apertures 18 through which the locking bolts 19 are adapted to extend into engagement with the serrations or teeth 11 provided on 75 the shanks of the staple or U-shaped member 10. The bolts 19 are reduced as at 20 at their inner ends, said reduced portions being adapted to slidably engage within the sleeves 21 and being provided with oppositely projecting pins 22 which are designed to engage 80 within the slots 23 provided in said sleeves 21 in such wise as to limit the movements of said bolts in both directions. The inner ends 85 of the sleeves 21 are provided with suitable screw-threaded plugs 24 between which plugs and the inner ends of the bolts 19 are positioned coiled springs 25 adapted to urge 90 said bolts outwardly and to normally maintain them in their projected positions substantially as shown in Fig. 2 of the drawings. The bolts 19 and the sleeves 21 are also preferably constructed of hardened steel so as to lend rigidity and strength to the lock and further, to provide against all 95 attempts to break the lock or render it otherwise ineffective by the use of force.

The front wall of the casting 14 is preferably provided with a central screw-threaded aperture 26 adapted to receive a barrel or 100 drum 27 which is designed to contain the lock controlling mechanism (not shown) which may be of any suitable type, said barrel or drum being provided with the usual key opening in order that a key of 105 special design may be inserted therein for the purpose of manipulating the locking mechanism. A suitable set screw is shown at 28 which serves to maintain the barrel or drum 27 in its proper adjusted position. 110

The barrel 27 is provided at its inner end with a suitable rotatable member 29 which

is operatively connected in any suitable manner to the mechanism housed within said barrel and which is accordingly controlled and operated thereby upon a proper movement of the key. Attached in any suitable manner at opposite ends of this rotatable member 29 are toggle members 30, the outer ends of which are pivotally secured by means of the screws 31 to the inner ends of 10 the sleeves 21, as shown more clearly in Figs. 2 and 3.

It is desirable to provide suitable guides for the sleeves 21 and with this in view, it is preferred to cast integral with the housing 14 suitable upstanding lugs 32 which are apertured as at 33 to receive said sleeves and to permit of them reciprocating therethrough. The cover plate for the locking mechanism is shown at 34, the same being 20 preferably formed of metal of channel construction, as shown more clearly in Fig. 4, the sides of said cover being designed to frictionally engage the sides of the housing 14 so as to maintain said cover in position. 25 The sides of the guiding lugs 32 terminate short of the sides of the housing 14 in order to permit of the sides of the cover 34 reaching substantially to the bottom of the chamber 15 when in position. 30 It will also be noted that when the cover is in position the same engages the lugs 32 not only on the sides thereof, but also on the top, as shown more clearly in Fig. 4. No means for holding the cover in position, 35 other than the frictional engagement of the sides thereof with the sides of the casting, need be provided, as will hereinafter appear.

The teeth or serrations 11 provided on the 40 staple or U-shaped member 10 of the lock are so designed that the locking member proper, which is designated as 13, may be pushed or moved inwardly in such wise that the bolts 19 will snap successively into 45 the intervening recesses automatically as a result of their being yieldingly urged normally outwardly by means of the coiled springs 25. In other words, no manipulation of the lock controlling mechanism by 50 means of the key is necessary to effect an engagement of the bolts with the teeth or serrations 11. On the other hand, however, it will be noted that it is necessary to manipulate the lock controlling mechanism by 55 means of the key in order to retract or withdraw the bolts from engagement with the teeth or serrations 11 so that the locking member proper 13 may be removed from the U-shaped member 10 in order to disassemble 60 the lock when it is desired to remove the tire or tires held thereby. This withdrawal of the bolts is effected by turning the key in the proper direction whereupon the member 29 is rotated in such wise as to retract the sleeves 21 by means of the toggle 65

members 30, which movement of the sleeves 21 effects a corresponding retraction of the bolts 19 by means of the pin and slot connections therebetween. As soon as the bolts have been thus retracted, it is apparent, as 70 above described, that the locking member 13 may be removed from the staple or U-shaped member 10, thus effecting a disassembly of the lock.

It is apparent from the above that a lock 75 has been provided which may be used for the purpose of locking one or more tires to their supports without any change or alteration therein being necessitated. In Fig. 1 the lock is shown applied to a plurality 80 of tires, said tires being shown supported in the usual manner upon a tire rack of the ordinary twin construction. When it is desired to use the lock for the purpose of locking more than one tire, said lock is preferably applied in a substantially horizontal position as shown, whereas when the lock is used in connection with a single tire, it may be applied in a substantially vertical position as shown more clearly in Fig. 5 85 90 wherein one tire is shown supported on the ordinary expandable type of tire carrier. It is, of course, obvious that when applied to a single tire and its support the lock may be positioned horizontally, if desired, or in any other position that may prove convenient or advantageous.

In Fig. 6 the lock is shown as used for locking a tire to the rear part of the frame of the automobile and in order to render 100 said lock adaptable for such an application the top of the U-shaped member or staple 10 is preferably angularly offset from the shanks or legs thereof so that both the tire and the frame may be securely and snugly 105 engaged in order to prevent any free play between the lock and the various parts embraced thereby.

From the above it is believed to be apparent that a lock has been provided which 110 is not limited in its adaptation to the locking of tires to their supports or tire racks but one which may also be used in the locking of tires to the automobile itself or parts thereof and with this in view it is to be understood that it is within the contemplation of the present improvements to so construct the staple or U-shaped member 10 as to permit of the spare tires being 115 locked to any portion of the automobile 120 which may prove most advantageous. The lock has also proved very effective in preventing thefts of automobiles by locking one of the front wheels thereof to the adjacent spring or some other part of the car. 125 It will, therefore, be apparent that the lock is not limited in its use to tires but, on the other hand, is of much broader adaptation and may be used for many other purposes.

In applying the lock it is merely neces- 130

sary to position the staple or U-shaped member over the tire or tires to be locked and to then insert the shanks or legs thereof into the apertured wings or lugs 12 and move or 5 push the locking member 13 up tightly against the tire or its support substantially as shown in Fig. 1. As above described, the inner edges of the sides of the casting 14 are curved as at 16. By referring to Fig. 10 it will be noted that this permits of the locking member 13 readily adapting itself to the contour of the tire rack or tire in contact with which said locking member is moved. In other words, the inwardly 15 curved contour of the locking member 13 is to permit of its snugly fitting the tire or tire rack when said member is pushed into firm contact therewith in which position it is securely held by means of the engagement of the bolts 19 with the teeth or serrations provided on the shanks or legs of the U-shaped member 10. This, it will be noted, not only renders the lock rigid when 20 in its final position but also provides means 25 whereby the tire or rack, against which the locking member 13 is held, effectively obstructs all access to the cover 34 and hence to the locking mechanism housed thereunder in the chamber of the casting 14. Accordingly, it is unnecessary to provide any 30 means for fastening the cover in position other than the sides thereof which maintain said cover against accidental displacement by frictional engagement with the sides of the casting, as above described. The 35 portion of the staple which contacts with the tire rack or other parts of the automobile is preferably covered with tubing of rubber, as shown at 35, or some other suitable material in order to prevent any marring or scratching of the parts or other similar injury.

It will also be noted by referring to Fig.

1 of the drawings that the lock comprises no accessible or exposed parts such as might 45 afford means whereby the lock could be broken, tampered with or otherwise impaired or rendered ineffective. In other words, a very rugged and rigid lock is provided which may only be removed by a 50 proper manipulation of the lock controlling mechanism thereof by one in possession of the key thereto.

It is obvious that various changes and modifications may be made in the construction herein illustrated and described and accordingly it is not desired to restrict or limit the invention except where limitations appear in the appended claim.

What I claim is:—

A lock comprising an embracing member provided with teeth, a locking member in the form of a one-piece casting adapted to fit said embracing member and to be moved therealong into engagement with the article 65 to be clamped, a chamber in said casting, a plurality of guides integral with said member and projecting into said chamber, sleeves slidably mounted within said guides, locking bolts slidably mounted in said 70 sleeves, means for yieldingly maintaining said bolts normally projected through the end walls of said member into engagement with the teeth of said embracing member, means for limiting the forward and reverse 75 movements of said bolts, key-controlled mechanism, means connecting said sleeves therewith whereby said sleeves and bolts may be retracted, and a cover for said parts, the side walls of said member being designed 80 to snugly fit the article clamped whereby access to said cover and said parts is effectively obstructed.

In testimony whereof I have subscribed my name.

THOMAS C. COOPER.
